(57) **CLAIM**

The ornamental design for a drawer and door handle, as shown and described.

DESCRIPTION

FIG. 1 is a front perspective view of a drawer and door handle showing our new design;

FIG. 2 is a front view of the drawer and door handle shown in FIG. 1.

FIG. 3 is a back view of the drawer and door handle shown in FIG. 1.

FIG. 4 is a top-down view of the drawer and door handle shown in FIG. 1.

FIG. 5 is a bottom-up view of the drawer and door handle shown in FIG. 1; and,

FIG. 6 is a side elevational view thereof, the opposite side is a mirror image.
